Patented Oct. 20, 1914.

UNITED STATES PATENT OFFICE.

MILTON D. GOOD, OF ALBANY, OREGON.

REFLECTOSCOPE.

1,114,605.

Specification of Letters Patent. Patented Oct. 20, 1914.

Application filed November 26, 1913. Serial No. 803,249.

To all whom it may concern:

Be it known that I, MILTON D. GOOD, a citizen of the United States, residing at Albany, in the county of Linn and State of Oregon, have invented new and useful improvements in Reflectoscopes, of which the following is a specification.

This invention relates to a reflectoscope or device for supporting photographs, picture cards and the like so that the subject matter thereof may be viewed on an enlarged scale in a magnifying mirror, the object of the invention being to provide a simple, inexpensive and efficient device of this character which permits of the ready and convenient adjustment of the picture support and mirror relative to each other as occasion may demand, and which also permits of the convenient folding or closing of the parts in compact form when not in use or for storage or transportation.

The invention consists of the features of construction, combination and arrangement of parts herein fully described and claimed, reference being had to the accompanying drawing in which:

Figure 1 is a perspective view of a reflectoscope embodying my invention, showing the parts thereof in position for use. Fig. 2 is a vertical longitudinal section of the same. Fig. 3 is a vertical transverse section on the line 3—3 of Fig. 2. Fig. 4 is a side elevation of the device in closed or collapsed condition. Fig. 5 is a front elevation of the device as shown in Fig. 4. Fig. 6 is a perspective view of the combined holder and focusing device.

The device comprises a pair of rectangular members 1 and 2, which may be termed base and top sections, and which are coextensive in dimensions with each other. The sections are hingedly united at one edge, as shown at 3, so that they may be folded in parallel relation, also that the section 2 may be swung upward to a position at right angles or less to the section 1, as will be readily understood. The respective sections may be made of blocks of wood or other material, and the section 1 is provided in its sides with metal lined longitudinally extending guide grooves 4, and while the section 2 is suitably recessed upon its inner face to receive a concaved magnifying mirror 5, which may be of any preferred dimensions and magnifying and reflecting powers.

A suitable catch device 6 is provided for

uniting the free front edges of the sections 1 and 2 when the device is closed or the sections folded in parallel relation, as shown in Figs. 4 and 5.

Pivoted at one end to one of the sides of the section 1 is a bracket arm 7, which is adapted to support the section 2 in an upright position. This bracket arm is provided in one of its edges with a series of openings 8 to interlock with a headed stud 9 on the section 2, whereby said section 2 may be held at different angles to the base 1 as occasion may require in the use of the device in order to enable the pictures to be shown at the proper angle to the observer. The arm 7 is provided in its opposite longitudinal edge with a notch 10 adapted to interlock with a headed stud 11 on the section 1, for holding said arm in an out-of-the-way position when the device is closed or folded up. The photographs, the picture cards or the like are adapted to be mounted upon a holder 12 made of sheet metal or other suitable material. This holder comprises a body or front portion 13 and sides 14 bent rearwardly therefrom and at right angles thereto, a supporting flange 15, and guide flanges 16. The supporting flange 15 is bent upward from the lower edge of the body 13 to a position in parallel relation thereto to provide a groove to receive the lower edge of the card or picture, whereby the same may be held in contact with the body 12 in position to face the mirror 5. The lower end walls 14 extend downward below the plane of the wall 13 on opposite sides of the section 1 and have their lower ends inturned to form the flanges 16 which travel in the guide grooves 4, whereby the holder is supported in position and is slidably adjustable relatively to the mirror 5 to properly focus the picture.

It will be understood from the foregoing description that in the use of the device the section 2 is turned up and locked by the bracket arms 7 and stud 8 at a proper angle to the section 1, and that the picture or photograph to be viewed is mounted upon the holder 12, which holder is then slidably adjusted toward or from the mirror 5 until the picture is properly focused and reflected from the mirror, thus enabling a clear view of the picture on an enlarged scale to be obtained. When it is desired to fold or collapse the device when not in use or to enable it to be conveniently carried, packed, etc.,

the holder 12 is slid forwardly out of the groove 3 and then turned over or reversed so that the normal rear face of its wall 13 will rest upon the top of the section 1, its 5 sides 14 depending at the sides of the section 1, and the flanges 16 abutting against the front edge of said section 1, whereupon the section 2 may be closed down and secured in collapsed position to the section 1 by the 10 latch 6, the holder 12 thus being confined between the sections. When the holder 12 is so disposed the supporting flange 15 projects upwardly therefrom to an extent substantially equal to the distance at which the rear 15 edges of the sections 1 and 2 are spaced by the hinge 3, thus provided for its proper reception between the collapsed sections without liability of injury, as well as a clamping action by which the holder is held 20 between the sections 1 and 2 from movement.

I claim:—

1. A device of the character described comprising a bottom section, a top section hinged to the bottom section and provided 25 upon the inner side thereof with a magnifying reflector, means for holding the top section at a desired angle to the bottom section, means for holding said sections in folded or collapsed condition, and a card or picture 30 holder adjustably mounted upon the bottom

section and reversible to lie in contact with the upper face of the bottom section between said section and the collapsed top section when the device is closed.

2. A device of the character described 35 comprising a bottom section having guide grooves in its side edges, a top section hinged to the bottom section and provided upon the inner side thereof with a magnifying reflector, means for holding the top section at 40 a desired angle to the bottom section, means for holding said sections in folded or collapsed condition, and a card or picture holder comprising a front wall having an upturned card supporting flange at its lower edge and 45 provided with rearwardly bent side walls adapted to depend along the side edges of the bottom section and provided with inwardly extending flanges to slidably engage the grooves therein, said holder being 50 reversible to lie in contact with the upper face of the base section and between said section and the collapsed top section when the device is closed.

In testimony whereof I affix my signature 55 in presence of two witnesses.

MILTON D. GOOD.
